This technical drawing illustrates a complex mechanical assembly, likely a valve or actuator, with numerous numbered callouts pointing to specific parts. The components include various types of valves, a central cylinder, and connecting rods. The numbers range from 201 to 313, with some numbers appearing multiple times. The drawing is highly detailed, showing internal parts like valve stems, seals, and mounting hardware.

UNITED STATES PATENT OFFICE.

CESARE CAMPUS, OF NEW YORK, N. Y.

BOOK-MATCH MACHINE.

1,073,394.

Specification of Letters Patent. Patented Sept. 16, 1913.

Application filed May 8, 1913. Serial No. 766,284.

To all whom it may concern:

Be it known that I, CESARE CAMPUS, a subject of the King of Italy, residing in the borough of Manhattan, city, county, and 5 State of New York, have invented an Improvement in Book-Match Machines, of which the following is a specification.

My invention relates to machines for making what are commonly termed book 10 matches, that is to say, match cards provided with covers of flexible material for protecting the same.

The machine made in accordance with my present invention includes mechanism by 15 which the match card covers are cut from a reel of suitable paper stock, or other similar material, which is fed intermittently between each cutting operation so that the match card covers are of uniform width. 20 The match cards are preferably made in the form shown and described in Letters Patent No. 1,055,875, granted to me the 11th day of March, 1913, for an improved match card, and are fed, manually, to the machine and 25 moved intermittently and in unison with the traveling match card covers, the match cards also being cut intermittently and each section thereof, provided with a plurality of matches, is fed preferably by being per- 30 mitted to drop by gravity onto its match card cover. In the continued travel of the conveyer for intermittently moving the match cards and their covers so assembled, the covers are folded over into position on 35 match cards, each match card and its cover are suitably connected by a stapling or stitching mechanism, and each match card cover is then provided, on a portion of its surface, with a strip of frictional paint or 40 other material against which the matches must be scratched to light the same.

The machine comprising my invention also includes mechanism for imparting the necessary intermittent movement to the conveyers for carrying the match card covers and match cards, mechanism for embossing or printing the strip of paper stock before the same is cut to form match card covers, devices for feeding the strip of paper stock, 45 and devices for clamping the parts of the match card covers in position while the same are connected by stitching or stapling to the match cards, as well as suitable means for actuating all the hereinbefore means devices,

all of which will be hereinafter more particularly described. 55

In the drawing, Figure 1 is an elevation of one end of the machine embodying my present invention, and Fig. 2 is an elevation of the other end of the machine, these figures, being placed end to end, illustrating a complete elevation of the machine. Fig. 3 is a plan of those parts of the machine as shown in Fig. 1. Fig. 4 is a plan of those parts of the machine shown in Fig. 2. Fig. 5 is an enlarged cross section on line 5, 5, Fig. 1. Fig. 6 is an enlarged plan of the folder devices, by means of which the match card covers are folded to position over the match cards during the travel of the conveyer through the machine. Fig. 7 is a cross section on line 7, 7, Fig. 6. Fig. 8 is a cross section on line 8, 8, Fig. 6. Fig. 9 is a cross section on line 9, 9, Fig. 6. Fig. 10 is a cross section on line 10, 10, Fig. 6. Fig. 11 is a cross section taken substantially on line 11, 11, Fig. 6. (Figs. 7 to 11, inclusive, being on a larger scale.) Fig. 12 is a sectional elevation illustrating the mechanism by which the continuous rotary motion, as 80 applied to the machine, is converted into an intermittent rotary motion to drive the conveyers and the feed rolls, and other parts moved intermittently. Fig. 13 is a central transverse section of the parts shown in Fig. 85 12. Fig. 14 is a sectional elevation taken centrally through the embossing apparatus. Fig. 15 is a central sectional elevation of the feed rolls. Fig. 16 is a central sectional elevation illustrating the devices for cutting 90 the strip of paper stock to make the covers. Fig. 17 is a sectional elevation on line x, x, Fig. 16. Fig. 18 is a central sectional elevation showing the devices for cutting the match cards. Fig. 19 is a section on line 95 y, y, Fig. 18. Fig. 20 is an elevation of the cam for actuating the match card cutter, and Fig. 21 is a diagrammatic elevation illustrating the devices for actuating the means for retaining the cover in position while the 100 stitching operation takes place, actuating the pusher device for shifting the match books in the carrier.

Referring to the drawing, at one end of my improved machine, there is a base 20 105 and at the opposite end a base 21. I have illustrated the base 20 as supported upon suitable feet 22, and the base 21 on similar

feet 23, although, as will be understood, the bases 20 and 21 of the machine may be mounted on any suitable foundation. On the base 21 are fixed journal blocks 24 and 5 25, connected to which are bearings 26 and 27, in which there is mounted a drive shaft 28. On one end of this drive shaft, is a pulley 29, by means of which, through any suitable source of power, the shaft 28 is 10 driven. Also on the shaft 28 there are sprocket wheels 30 and 31, the function of which will be hereinafter described, and at the opposite end of the shaft 28 there is connected a crank arm 32, on the pin 33 of 15 which is the head 34 of a connecting rod 35.

36 represents a shaft which is mounted in suitable bearings 117 mounted on a suitable casing as hereinafter described. On one end of the shaft 36 is fixed a pulley 20 39 in suitably and equally spaced positions, in the periphery of which there are pins 40. On the base 21, there is connected a standard 41 and bearings 42, in which is 25 journaled a shaft 43, and on the shaft 43 is secured a pulley 44, similar to the pulley 39, including pins 47, which it may have on its periphery. The pulleys 39 and 44 are in 30 alinement with one another, and extending between and passing over the same is an endless belt conveyer 45, preferably made of any suitable sheet metal.

Secured to the outer surface of the endless conveyer belt 45, and in suitably and 35 equally spaced positions, there are spacer blocks 46. These may be connected to the belt by means of rivets, as clearly shown in Fig. 5, or in any other desired manner, and centrally in those portions of the endless conveyer belt intermediate of the blocks 40 46 are apertures 48, which are adapted to receive the pins 40 on the pulley 39 and the pins 47 on the pulley 44 so as to make the movement imparted to the conveyer from the drive pulley 39 not only positive but 45 equal for each intermittent movement of the belt.

The shaft 36 is driven by an apparatus 50 for imparting thereto a predetermined intermittent or step-by-step movement which apparatus will be hereinafter particularly described. On the end of the shaft 36 opposite to that carrying the pulley 39, there is fixed a gear wheel 49. This gear wheel 49 meshes with a gear wheel 50, mounted 55 on the shaft 51, which is journaled in suitable bearings 52, carried by the frame of the device *a*, by which the continuous rotary movement is converted into an intermittent rotary movement.

60 On the opposite end of the shaft 51, there is fixed a pulley 53. On the base 20 there is also a standard 54, carrying the journal block 55, mounted in the bearings 56 of 65 which there is a shaft 57. On one end of

the shaft 57 there is a pulley 58, which is 65 similar in all respects to the pulley 53, and extending between these pulleys 53 and 58 is a belt 59, which also is preferably made of sheet metal and provided with spaced apertures 60, into which pins 61 placed in 70 the peripheries of the pulleys 53 and 58 pass in order that the positive intermittent motion may be transmitted from the pulley 53 to the pulley 58 and its shaft 57.

On the opposite end of the shaft 57, there 75 is mounted a pulley 62, in the periphery of which and in equally and suitably spaced positions pins 63 are fixed. On the base 21 there is a standard 64 carrying a journal block 65, in the bearings 66 of which there 80 is mounted a shaft 67. Connected to this shaft 67 is a pulley 68, which, in its peripheral surface, is provided with equally and suitably spaced pins 69, the pulley 68 being 85 in all respects similar to the pulley 62. Passing over these pulleys 62 and 68, is an endless belt conveyer 70. This also is 90 preferably made of sheet metal, and in suitably spaced positions is provided with apertures 71, see Fig. 5, into which the pins 63 95 and 69 on the pulleys 62 and 68, respectively, are adapted to pass so that the movement imparted to the endless belt conveyer 70 is also positive. Also secured in suitably and 100 equally spaced position to the endless conveyer belt 70 are fingers or projections indicated at 72. These, as shown in Fig. 5, may be fixed to the belt by means of rivets 73 or otherwise. The functions of these fingers will be hereinafter particularly 105 described. Suitably connected to and rising from the block 55 is a bracket 74, and similarly connected to and rising from the journal block 65 is a bracket 75, and extending between and connected to the brackets 74 110 and 75 is a guard plate 76, in which the upper portion of the endless belt 70 travels. Secured to the base 21, there is also a standard 77, and extending between this standard 77 and the standard 54 on the base 20 is a 115 match card feeding table, preferably comprising a pair of support plates, indicated at 78, spacing plates, indicated at 79 and 80, and a bridge plate 81, connected to the spacing plates 79 and 80 by screws 82 or otherwise, see Fig. 5. At the forward edge of these spacing plates 79, and extending over a portion of the bridge plate 81, is a guide plate 83, adjustable to position laterally of the table by being secured to the spacing plate 79 by means of the screws 84, the heads of which are set in recesses in the adjustable plate 83, these recesses being larger than the heads of the screws in order that the plate 83 may be laterally adjustable to position.

120 Along the rear side of this feeding table, and extending upwardly therefrom, is a stop plate 85. As indicated in Fig. 5, this may 125

be secured to the spacing plate 80 by means of the bolts 86 or otherwise. In the member including the stop plate 85, there is a longitudinal undercut recess 87, in and through which the lower portion of the endless belt 70 passes. Directly beneath the stop plate 85, and spaced therefrom, is a rib 89, and through the slot between the upper surface of this rib 89 and the lower extremity of the stop plate 85 the series of projections or fingers 72 extend, these fingers, at their ends, being turned out so that their extremities are adjacent to the upper surface of the bridge plate 81 and their inner surfaces contact with or are adjacent to the upper face of the rib 89.

The apparatus comprising the mechanical movement by which the continuous rotary motion of the shaft 28 is transmitted to the shaft 36 in the form of an intermittent rotary motion, is indicated at *a* in Figs. 1 and 3, and shown in detail in Figs. 12 and 13. This preferably consists in a base 90 provided at one end with a head member 91 and at the opposite end with a head member 92. In the head member 91, there is a bore, and similarly in the head member 92 there is a bore, the former bore being of materially larger diameter than the latter. Mounted to reciprocate in the bore on the said heads, is a piston or plunger 93, one of which, as will be understood, fits and is movable within the bore in the head 91, and the other, of smaller diameter, fits and is movable in the bore of the head 92. As shown in Fig. 13, the ends of this reciprocating piston are preferably hollow, and in the one of the larger diameter, and on opposite sides thereof, there are bores 94 provided with bearings to receive a pin 95, by means of which one end of the connecting rod 35 is attached to the reciprocating piston 93. The opposite end of this connecting rod 35, as hereinbefore described, is connected to the drive shaft 28 by the crank arm 32, whereby the turning of the shaft 28 causes a horizontally reciprocating movement of the piston or plunger 93.

In the central portion of the reciprocating piston 93, and extending vertically therethrough, is an aperture 96. In this aperture there is fitted a vertically reciprocating member 97. At its upper end, this member 97 is provided with an inclined face 99 which, at the side distant from the connection with the rod 35, terminates in a rounded portion or nose 98. The vertically reciprocating member 97 is also preferably hollow, as indicated at 100, and within the same is a spring 101, extending from the end of the bore in this member to a cross arm 102, which extends across the vertical aperture 96 in the central portion of the reciprocating plunger 93, and is secured in re-

cesses provided therefor in the faces defining the said aperture 96. Fixed on the heads 91 and 92 is a casing 103, to the upper member of which there is fixed or suitably secured standards 104 and 105, which support the bearings for the auxiliary shaft 70 51. This casing 103 is designed to inclose a revoluble member, such as the wheel 106, which, within the casing, is secured to the shaft 36. In the periphery of this wheel, there is a series of equally spaced recesses 75 107, each of which is curved to conform with the nose 98 on the end of the vertically reciprocating member 97, and intermediate of each of the recesses 107 of the periphery of the wheel there is a flat inclined face 108, these inclined faces being made at the same angle at which the face 99 on the upper end of the vertically reciprocating member 97 is inclined. These parts are so designed that the extent of the 80 reciprocating movement of the plunger 93 is just sufficient to cause the ends 98 of the vertically reciprocating member to successively engage the recesses in the periphery of the wheel 106, thereby, with each reciprocation of the plunger 93, turning the wheel 106 a predetermined portion of a revolution.

Secured within the base 90, and immediately below the vertically reciprocating member 97, is a block 99^a. The lower surface or end of the vertically reciprocating member is inclined so as to be parallel with its upper face 99, and the upper face of the block 99^a is also inclined at the same angle, so that 95 the lower face of the member 97 contacts with the slides upon the same.

It will now be apparent that when the parts have reached the position shown in Fig. 12, the nose 98 engaging one of the 105 recesses 107 in the wheel, the face 99 contacting with the adjacent face 108 of the wheel, and the lower end of the vertically reciprocating member being in contact with the face of the block 99^b, the parts will be 110 positively locked in position, thus preventing the further movement of the wheel in either direction. This position of the parts, it will be understood, is at the end of the forward stroke of the reciprocating piston 115 93, in the return movement of which the vertically reciprocating member 97 is forced downwardly against the face 108 in the periphery of the wheel until, at the end of its return stroke, the horizontally reciprocating piston is in such a position as to permit the spring 101 to force the vertically reciprocating member 97 upwardly again to engage the next succeeding tooth in the periphery of the wheel.

I may further employ a ratchet wheel 109, mounted on the shaft 36 and adapted to be engaged by a pawl 110, mounted on

a lug 111 on the casing 103. Secured to the pawl 110 is an arm 112, and the pawl may be maintained in normal engagement with the teeth of the ratchet by means of a spring 113, which extends from the end of the arm 112 to a suitable connection therefor attached to the casing 103.

The reciprocating parts of this apparatus are preferably operated in oil, and for this purpose covers 114 are provided at the opposite sides of the heads 91 and 92, and within these covers there are guides 115, between which the central portion of the reciprocating plunger operates. On the head 92, there is a cap 116, and the casing may be further provided with a well, a portion of which is indicated at 116^a, in order to receive any overflow of the oil bath which may escape from the casing. Furthermore, portions of the casing 103 may be provided with bearings 117 and bushings 118 for the shaft 36. This apparatus and its operation are more fully described in my co-pending application, Serial No. 761,904, filed 25 Apr. 18, 1913, for an improved mechanical movement. The intermittent movement imparted to the shaft 36, as hereinbefore described, will, as will be understood, be also imparted to the pulleys 40 and 44, causing a correspondingly uniform intermittent movement to be imparted to the endless conveyer belt 45, and furthermore this movement will also be imparted to the endless conveyer belt 70 by means of the pulleys 53 and 58 and the belt 59. On the shaft 36 there is also fixed a gear wheel 119. This gear wheel 119 meshes with a gear 120, fixed on a shaft 121, journaled in bearings 122 connected to and depending from the frame in which are the bearings for the shaft 51. The gear 120 meshes with a gear 123, which is secured to a shaft 124 mounted in suitable bearings 125, the bearings 125 being secured in position on the standards 126 and 127. See Figs. 1, 3 and 15. Upon the shaft 124 is a feed roll 128, in the periphery of which there is preferably provided a series of recesses 128^a, in order, as will be hereinafter described, not to destroy 50 the embossing which may be placed upon the material fed between this roll and its cooperating roll.

The feed roll 128 is contained within a feed roll case 130, within which there is also an adjustable feed roll 131. This feed roll is secured on a shaft 132, preferably provided with a bushing 133 and journaled in the sides 134 of a movable frame 136, the sides 134 of the frame 136 being provided 60 with ribs 135 extending into recesses provided therefor, and within which the side ribs are movable to guide the frame in the movements thereof.

The rod 137 is connected at one end to

the upper portion of the frame 136. This 65 rod 137 extends through a gland 138, adjustable to position in a cover 139 of the feed roll case, exteriorly of which, and at the upper end of the rod 137, there is a hand wheel 140. The gland 138 is preferably screw threaded exteriorly, in order that it may be adjusted to position in the cover 139, and on this screw threaded portion of the gland is a nut 141, employed to lock the gland in position. The gland is also provided with a bore, within which there is a spring 142 extending from the base of the bore to the upper portion of the movable frame 136, surrounding, as it will be understood, the intermediate portion of the rod 137. 80

It will be understood that the adjustment of the glands to position varies the tension exerted by a spring against the movable frame, and consequently determines the pressure with which the adjustable feed roll 85 normally bears against the feed roll 128, and, as will be further understood, the hand wheel 140 may be turned down against the outer end of the gland 138 to raise the movable frame against the action of the spring 90 142 to separate the feed rolls. These feed rolls are indicated at *b* in Figs. 1 and 3, and are shown in sectional detail in Fig. 15.

The embossing mechanism is indicated at *c* on Figs. 1 and 3, and is shown in detail 95 in Fig. 14. This embossing mechanism is driven from the main shaft 28, on which there is a sprocket 143, shown in broken lines in Fig. 2. Over this sprocket is a sprocket chain 144, which also passes over 100 a sprocket 145 fixed on a shaft 146 and journaled in suitable bearings 147, the bearings 147 being mounted on standards or columns 148, 149 which are supported upon the base 20.

At one end of the shaft 146 there is a fly wheel 150, (see Fig. 3 only) and in suitable positions connected to the shaft are crank arms 151, having the usual crank pin 152, to which, at one end, the connecting rod 153 is secured. By a pin 154 the opposite end of the connecting rod 153 is connected to a reciprocating rod 155. This reciprocating rod 155 is adapted to move vertically in suitable bearings 156 secured 110 to the standards 148 and 149. A second reciprocating member 157 is journaled and adapted to move vertically in bearings 158, also secured to the standards 148 and 149, and connecting the reciprocating rods 155 and 157 is a member 159. This member 159 is provided with screw threaded portions, which are adapted to be received in tapped bores provided therefor in the reciprocating rods 155 and 157, so as to adjust the positions of these reciprocating rods 120 relatively to one another, and on the screw threaded member 159 there are nuts 160 and 125

161 adapted respectively to secure the member 159 in position in the reciprocating rods 155 and 157.

Connected to and suitably spaced apart 5 from the upper end of the reciprocating member 157 is a head 162. Mounted on the upper ends of the standards 148 and 149, is a frame 163, in which a die block 164 is mounted to move in suitable guide-ways provided therefor in the frame. This die block 164 adjacent to its lower end is provided with a recess 165, adapted to receive the head 162 in order to connect the die block with the reciprocating rod 157. 10 In the upper surface of the die block 164, a die 166 is suitably secured. Above the die block 164 and die 166, there is a fixed block 167, carrying in its lower surface a die 168, adapted to coöperate with the die 166, and this fixed die block 167 is suitably secured in the frame 163 and its cap 169. 15 Adjacent the dies 166 and 168, the frame 163 is provided with recesses 170, through which the paper stock passes in being fed 20 through the machine.

The parts of the apparatus are so timed that with each revolution of the shaft 146 and the consequent reciprocation of the die block 164 and its die 166, each time the strip of paper stock is stationary, due to the intermittent feed, the coöperating dies 164 and 166 are brought together with the strip of stock intervening to suitably emboss the same. It will further be understood that instead of employing an embossing mechanism at this point, in the manufacture of the book matches a printing mechanism may be employed.

Suitably secured to the upper portions of 40 the standards 148 and 149 is a bracket 171 (Figs. 1 and 3) adapted to carry a weight member 172 which extends a greater portion of the distance between the embossing mechanism, hereinbefore described, and adjacent side of the feed rolls, and is adapted 45 to contact with and bear against the paper stock with more or less pressure, in order to prevent the same from becoming crumpled, so as to insure a proper and uniform 50 feed of the stock.

The devices for cutting the rolled paper stock to form the match book covers are indicated at *d* in Figs. 1 and 3, and are shown in detail in Figs. 16 and 17. These 55 devices are driven from the sprocket wheel 30 and the shaft 28, the sprocket chain 173 passing over the sprocket 30 and also over a sprocket 174, mounted on a shaft 175 which is journaled in bearings 176, supported upon a block 177, which is suitably 60 secured to the base 20. On the shaft 175 there is also a sprocket 178, over which a sprocket chain 179 passes. The chain 179 also passes over a sprocket 180 fixed on the

shaft 181, which is journaled in bearings 65 182 supported upon a frame 183, which is connected to standards 184 with an intervening spacer plate or bed 184^a.

In the frame 183 is mounted, to reciprocate vertically, a knife block 185. A knife 70 186 is connected to the knife block 185 by means of bolts 187 or otherwise, and at its opposite sides the knife block 185 is provided with guides 188 which move in suitable guide-ways 189 provided therefor in 75 the frame 183. Extending into these guides 188 are rods 190, each provided with a shoulder 192 extending between which and the spacer plate 184^a is a spring 191.

Suitably secured on the upper face of the 80 knife block 185 is a bearing block 193 in which is fixed a shaft or arbor 194, upon which a roller 195 is revolvably mounted. On the shaft 181, between the bearings 182, there is fixed a cam 196 adapted to bear 85 against the surface of the roller 195, and this roller is normally maintained in contact with the face of the cam by means of the action of the springs 191.

In the operation of the apparatus, the 90 strip of paper stock forming the match card covers is fed intermittently along the upper surface of the spacer plate 184^a, and each time the feeding of the paper stock stops the knife block 185 is forced downwardly by means of the cam 196 and roller 195 to cause the knife 186 to sever or cut off a portion of the stock strip to form a match book cover, and when so severed from the stock strip, each match card cover drops 95 100 by gravity on the endless belt 45 between adjacent blocks 46 thereof.

The devices for cutting the match cards into sections for each match book cover are indicated at *e* in Figs. 2 and 4, and are 105 shown in detail in Fig. 18. These devices comprise a cam 197 (see Fig. 20), which cam is fixed on the drive shaft 28 and is provided in one face with a cam groove 198, in which operates a roller 200 which is suitably connected to a reciprocating head 199, 110 which is adapted to slide in suitable ways, provided therefor, in one of the standards or columns 77, the bearings for this reciprocating head being indicated at 201.

In the reciprocating head 199 is fixed one end of a reciprocating rod 202, the upper portion of which is adapted to slide in a bearing 203, which is also suitably connected to the standard 77. To the upper 120 end of the reciprocating rod 202, one end of a connecting rod 204 is pivotally connected. The opposite end of this connecting rod 204 is pivotally connected to one end of a rocker bar 205, which is fixed on a 125 rocker shaft 206, journaled in bearings 207, which are made integral with or suitably connected to a frame 208. This frame 208-

is placed upon the spacer plate or bed 209, which is supported on the upper ends of the standards or columns 77, and these parts are suitably secured together.

5 Reciprocating vertically in the frame 208 is a knife block 210, secured to one side of which, by means of bolts 212, or otherwise, is a knife 211. The upper end of the knife block 210 is pivotally connected to the rocker bar 205 by means of a link 213, so that the reciprocating movement of the knife block and knife is effected through this link, the rocker bar 205, the connecting rod 204, the reciprocating rod 202, the head 199 and 10 its connection with the cam 197. The knife block 210 is preferably mounted in bearings 214, in which it reciprocates, and this knife block is also preferably made hollow, the bore thereof being indicated at 215. Mov- 15 able longitudinally within this bore 215, is a presser bar 216, to which, at its ends, exteriorly of the knife block, is a presser foot 217, and this presser bar and presser foot are maintained in a normal position by 20 means of a spring 218, which extends from the base of the bore in the knife block, through a similar bore in the presser bar and to the base thereof. These parts are so timed that each time the match cards are 25 arrested in their movement, the presser foot is brought down to clamp the match card against the spacer plate 209, and, as will be apparent, the continued downward movement of the knife block brings the knife 211 30 into contact with the match card, severing the same into the required length sections, each of which, as severed, falls into one of the spaces between the blocks 46 on the conveyer belt 45, and upon its match book cover. The spacer plate 209, as will be understood, is provided with an edge which co-operates with the knife in cutting the match strips.

Supported upon and suitably connected 45 to the standards 64 and 77, is a plate 219, and connected to this plate 219 is a plate 220, with intervening plates 221, 222 and 223, as is clearly illustrated in Fig. 7.

The position of each match book cover, 50 as well as that of each group of matches, as the same are received in a superimposed position between the blocks 46 on the conveyer belt 45, is indicated at the right hand portion of Fig. 6, in which, as will be seen, 55 one end 224 of the match book cover overhangs one edge of the conveyer belt, while the opposite end 225 of the match book cover overhangs the opposite edge of the conveyer belt, the end 224 being the short 60 end which is overturned against the base of the match card, while the end 225, after being folded over, forms the cover or flap of the match book. In order to insure this 65 position of the match card cover in its place in the conveyer belt, a guide arm 226 is

adjustably fixed on the plate 219. In being moved by the conveyer belt, the forward edge of the end 225 of the match card cover contacts with the adjacent surface of this guide 226, and if by chance the match card cover should not be in its proper position, the movement thereof with its edge in contact with the surface of the guide 226 would shift it to the proper position, in which, as will be seen in Figs. 6 and 7, the opposite or shorter end 224 of the match book cover is in contact with the adjacent surface of the intermediate or spacing plate 223.

Suitably connected to a bracket 228, fixed on the plate 219, as a folder 227, the edge of which is inclined so as to engage the outer surface of the end 225 of the match book cover in order, in its continued movement, to turn the same from the position shown in Fig. 6 to that shown in Fig. 7. 80 This, as will be understood, brings the adjacent portion of the cover against the heads of the matches and places the match card strip in its proper position, with the edge opposite the match heads in contact with the adjacent surface of the intermediate plate 222, as is also shown in Fig. 7.

In the position shown in Fig. 7, the covers and match strips are conveyed from the line indicated at 7, 7, Fig. 6 to the line indicated at 8, 8, therein, and during the travel between these positions the end 225 of the match book cover travels through a slot 231 between the edge of the plate 220 and the edge of a plate 230 fixed in a rib 229 on the plate 219. After having reached the point indicated at the line 8, 8, Fig. 6, the short end of the match book cover engages a folder 232 which is also suitably secured to the plate 219, and almost simultaneously therewith the longer end 225 of the match book cover comes into contact with a folder 233, the folder 232 turning up the short end 224 of the match book cover, as indicated in Fig. 8, and at this point, the folder 233 starts to turn over the long end 225 of the match book cover until the parts have traveled sufficiently far to reach the point indicated at 9, 9, Fig. 6, at which, as will be shown in Fig. 9, the long end 225 of the book cover has been completely turned over the match strips and the short end 224 of the cover is about to be turned down against the same, the tapered end 234 of the plate 220 acting to insure the short end 224 being maintained in its proper position until the long end 225 of the cover has been completely turned down.

In the further movement, that is, from the points indicated at 9, 9, Fig. 6, to that indicated by 10, 10, the short end 224 of the book cover is brought into engagement with the folder 233, which completely turns this short end over, causing the same to overlap the extremity of the 110

long end 225 which now forms the flap of the cover.

Secured in a bracket 237, adjacent to the folder 233 is a folder 236, the function of which is to turn up the long end of any match card cover blank so that the same may be readily withdrawn from the machine in the event of its not having been supplied with a match strip. If for any reason a section of match strip should not be properly placed within a pocket on the endless conveyer, it will be apparent that as the conveyer progresses, the long end 225 of the cover blank will not be properly turned to a right angle by means of the folder 227, and instead of standing in a vertical position as shown in Fig. 7, will stand in an inclined position. In this position it will be carried along by the conveyer and at a sufficient elevation to clear or come above the folder 233 so that in the further movement of the conveyer, this long end of the cover blank is engaged and further turned up by the folder 236 so as to be readily grasped by the operator and withdrawn from the machine. When in their movement the covers and the inclosed match strips have reached the position indicated by the line 11, 11, Fig. 6, the ends of the match cards opposite the heads of the matches, the short end 224, and the adjacent portion of the cover are stapled or stitched together by means of a suitable mechanism.

In suitable recesses provided therefor in the plate 219, I also may employ a roller 238 and a roller 239, passing around which is an auxiliary endless belt 240, which is adapted to move in a recess provided therefor in the inner edge of the plate 219 so as to contact with the outer surface of each match book cover, in order to prevent any friction which there would be between this portion of each match book cover and a stationary wall from damaging the covers. As indicated in the drawing, the contact between these portions of the match book covers and the auxiliary belt is the means of moving the belt, although, as will be understood, I may employ, if desirable, any suitable mechanism for positively driving this auxiliary belt at the same speed and to the same extent of intermittent motion as the endless belt 45 is driven.

The stapling or stitching mechanism employed in my improved machine is indicated by *f* in Figs. 2 and 4, but inasmuch as this apparatus *per se* is neither new or my invention, no detailed description thereof is thought to be necessary. The stitching mechanism, however, is driven by a sprocket chain 241 passing over the sprocket 31 on the shaft 28, and also over a sprocket 242 fixed on a suitable shaft on which a second sprocket is also mounted, over which a second sprocket and a sprocket 244, a chain

243 passes, the sprocket 244 being mounted on a shaft 245, by which the stapling or stitching mechanism is driven. The apparatus shown is preferably a stapling mechanism, the staples being made of wire 246 fed from the reel 247 so that the wire is cut and staples formed therefrom and driven by this mechanism to secure the parts of each match book together, as hereinbefore described.

Secured to the end of the rocker shaft 206, see particularly Fig. 21, is a rocker arm 248, and pivotally connected at one end to the end of this rocker arm is a connecting rod 249, the opposite end of which is pivotally connected to the end of a rocker arm 250, which is secured on a shaft 251 mounted in bearings 252 in suitable standards 253, one of which is fixed to the plate 219 and the other supported upon columns 253a. Fixed on this rocker shaft 251 is a rocker arm 254, and pivotally connected to the rocker arm 254 is an adjustable connection rod 255, the opposite end of which is pivotally connected at 256 to the free end of a rocker lever 257, which, at its opposite end, is connected to an arbor 258, journaled in bearings 259, fixed on a bracket 260, secured to the plate 219.

Connected to the free end of the rocker lever 257 is one or more yielding presser feet, indicated at 261. These are preferably made of rubber or other similar material and are adapted, when the match book is in position to be stitched, to be brought down upon the outer surface of the covers, as indicated in Fig. 11, to secure the parts of the book in position while the stapling or stitching takes place, the movement of the presser feet 261 being apparent from the diagrammatic illustration shown in Fig. 21 and the foregoing description thereof.

Also secured to the rocker shaft 251, is a rocker arm 262, the lower or short end of which is so connected to a plunger 263 as to cause the same to reciprocate transversely of the direction in which the endless belt 45 travels. Also connected to the rocker shaft 251 is another rocker arm 264, to which at one end is pivotally connected a connecting rod 265, the opposite end of which is pivotally connected to one end of a rocker lever 266, which, at 267, is pivotally mounted in bearings provided therefor in a bracket 268 which is suitably secured to the plate 219. The lower end of the rocker lever 266 is pivotally connected to one end of a plunger 269, which is also adapted to reciprocate in a direction, at right angles, to that in which the endless conveyer 45 travels.

The plungers 263 and 269 are moved in suitable slideways in opposite directions, as will be understood, to cause their adjacent bifurcated ends to pass over the adjacent portions of the match books to assist in se-

- curing the same in position during the stapling or stitching operation, these plungers 263 and 269 being moved into the space between the blocks 46 on the endless conveyer 45, and above the match books, and in contact with the same, while the stapling or stitching operation is effected, after which these plungers are withdrawn from the spaces between the said blocks.
- On the end of the rocker shaft 251, there is another rocker arm 270, the free end of which is suitably connected to a rod 271 for operating a pusher 272, the function of which is to shift each match book to the position shown in dotted lines at the left-hand end of Fig. 6. This, as will be seen, does not free the match book from the conveyer, but places the stapled or stitched end of the same against a guide-rail 272^a, in order that the match books, in being further conveyed through the machine, may have applied thereto the customary frictional substance to form a striking surface.
- The device for applying the frictional substance to form the striking surface of the covers of a match book is indicated at *g*, and preferably comprises a frame 273 fixed on standards or columns 274. Attached to the frame 273 is a bracket 275, in which there are bearings 276 in which a shaft 277 is journaled. On the shaft 277 is a sprocket 278 over which the chain 279 passes. This chain 279, as shown in the drawing, extends substantially the entire length of the machine and also passes over the sprocket 280 on the feed roll shaft 124, although, as will be apparent, this is only one means of driving this mechanism as other and probably more expedient means may be employed.
- On the shaft 277 is also fixed a sprocket 281. Passing over this sprocket 281, is a sprocket chain 282, which also passes over a sprocket 283 fixed on the shaft 284, also journaled in bearings suitably secured to the frame 273.
- On the shaft 284 is fixed a gear 285, a friction wheel 286, and another gear wheel 287. The gear 285 meshes with the gear 288 mounted on the shaft 290, on which there is also a friction wheel 289, the friction wheel 289 contacting with the friction wheel 286. This friction wheel 289 is in line with the edge of the guide rail 272^a and is the means by which the frictional surface is applied to the stapled end of the match books.
- The gear 287 meshes with a gear 291 fixed on a shaft 292, on which there is secured a friction wheel 292^a, the periphery of which contacts with the friction wheel 286 and also extends into the receptacle containing the paint or frictional material which is applied to form the striking surface of the match book covers. On the shaft 292 there is also, at its opposite end, a gear 293 which meshes with a gear 294 fixed on a shaft 295, on which there is a beveled gear 296 meshing with a similar gear 297 secured on a vertical shaft 298, to which is also secured a mixer arm 299, which is thus caused to revolve in the receptacle containing the liquid material of which the striking surface on the book covers is made. This vessel is provided with a cover 300, in which there is an opening 301 for inserting the paint and secured to which there are also eye-bolts 302, by means of which a cover may be removed from the receptacle. These parts, as will be apparent, are so constructed that the cover, with the shaft 292, the gears and friction wheel thereon, and the shaft 295 and gears thereon, may be entirely removed with the cover, in order that free access may be obtained to the interior of the vessel for cleaning the same, and other purposes.
- In the operation of the hereinbefore described machine, the shaft 28 is driven at a constant speed by suitable source of power, and the shaft 36 is driven from the shaft 28 through the mechanical movement apparatus indicated at 2, so as to have imparted thereto a regular intermittent revoluble movement.
- The feed rolls, indicated at *b*, are driven through suitable gears, as hereinbefore described, connecting the same with the shaft 36. The shaft 36 also drives the endless conveyer 45 and the endless conveyer 70, so that to these parts a regular step-by-step or intermittent movement is imparted.
- The strip of paper stock is preferably supported and fed from a reel to and through the embossing apparatus, indicated at *c*, to the feed rolls, by which, as it will be understood, the strip of paper stock is intermittently fed, the embossing apparatus being so operated that each time the feeding of the strip of paper stock ceases, the stock is embossed, or as hereinbefore stated, in lieu of the embossing apparatus, a printing apparatus may be employed and the paper stock printed upon it.
- By the feed rolls, the paper stock is regularly fed to the cover cutting apparatus, indicated at *d*. This is operated each time the feed of the paper stock ceases, so that a predetermined length thereof is cut off and permitted to drop by gravity within one of the pockets between the blocks 46 on the endless conveyer 45, the portion of the strip of paper stock so severed forming a cover blank for a match book.
- The match strips are fed manually to the machine by being first placed on the guide plate 83 and passed to position against the stop plate 85, with the recess in the edge of each match strip engaged by one of the fingers or projections 72, carried by the endless conveyer 70. These strips are progressively fed by this endless conveyer to the match strip cutter devices, indicated at *e*, and each time the endless conveyer 70 stops,

these cutter devices are actuated to sever a match strip section from a match strip card. Each match strip section, as severed, is permitted to drop by gravity into position upon its match card cover in a pocket between the blocks 46 on the endless conveyer 45. In the further movement of the endless conveyer 45, the ends of each match card cover blank are folded over its match card section by the series of folders, as hereinbefore described, and after being so folded, each match book, in turn, is brought beneath the stitching or stapling mechanism indicated at *f*, and each match strip section secured within its cover, a match book being so stitched or stapled each time the conveyer 45 is brought to a stop. During the still further continued movement of the endless conveyer 45, the pusher 272 is actuated to partially remove a match book from its pocket in the endless conveyer each time the same is brought to a stop, so as to place the same upon the table 303, and with a portion of the match card cover in line with the roller 289, by which, as hereinbefore described, each match book cover is provided with a strip of friction paint forming a striking surface for the matches, after which each match book is delivered from the machine 30 and into a suitable receptacle provided therefor. As the pusher 272 moves each match book in turn from its normal position in a pocket in the endless conveyer 45 to the position shown in dotted lines in Fig. 35 6, the stapled end of each match book is passed under the overhanging edge 304 of the guide plate 272^a so that with the continued movement of the conveyer 45 and as the same passes down over the pulley 44, each 40 match book in turn is removed from its pocket in the conveyer and placed on the table 303. The movement of each match book, when being placed on the table, forces the match books between itself and the roller 289, along a predetermined distance so as to cause each match book in turn to pass beneath the said roller 289 and after having applied thereto by this roller a strip of the friction paint, to pass from the machine to 50 the receptacle provided to receive it.

I claim as my invention:

1. In a machine for making book matches and in combination, a unitary means for receiving and conveying match book cover blanks and unattached match strips thereon, and devices co-acting with the said means while the same are conveying the said match book cover blanks and match strips for folding both ends of each blank to position over its match strip to form a cover therefor.

2. In a machine for making book matches and in combination, a unitary means for receiving and conveying match book cover blanks and unattached match strips there-

on, devices co-acting with the said means while conveying the said match book cover blanks and match strips for folding both ends of each blank to position over its match strip to form a cover therefor, and means for securing each match strip within its cover. 70

3. In a machine for making book matches and in combination, a unitary means for receiving and conveying match book cover blanks and unattached match strips thereon, 75 devices co-acting with the said means while the same are conveying the said match book cover blanks and match strips for folding both ends of each blank to position over its match strip to form a cover therefor, means for pressing each cover to position around its match strip, and means operative while the said covers are so pressed to position for securing each match strip within its cover. 80

4. In a machine for making book matches and in combination, an endless conveyer, means for feeding thereto match book cover blanks, means for feeding match card strips to the said conveyer so that each match card strip is placed upon a cover blank, and means co-operating with the said endless conveyer for folding both ends of each cover blank to position over its match strip while in the conveyer and during the movement thereof. 95

5. In a machine for making book matches and in combination, an endless conveyer, means for feeding thereto match book cover blanks, means for feeding match card strips to the said conveyer so that each match card strip is placed upon a cover blank, means co-operating with the said endless conveyer for folding both ends of each cover blank to position over its match strip while in the conveyer and during the movement thereof, 100 and means for securing each match strip within its cover while the parts are still in the conveyer. 105

6. In a machine for making book matches and in combination, an endless conveyer, means for feeding thereto match book cover blanks, means for feeding match strips to the said conveyer so that a match strip is placed upon each cover blank therein, means co-operating with the conveyer during the 110 movement thereof for folding both ends of each cover blank to position around its match strip to form a cover therefor, means for pressing the parts of the cover to position against its match strip, and means operative while each cover is in the said pressed condition for securing its match strip thereto. 115

7. In a machine for making book matches and in combination, an endless conveyer, means for feeding match book cover blanks thereto, a second endless conveyer parallel to the first endless conveyer for feeding match strips thereto so that a match strip is supplied and placed upon each match book cover blank, and devices co-acting with the 125 130

first aforesaid endless conveyer during the travel thereof for folding both ends of each cover blank over its match strip to position thereon to form a cover therefor.

- 5 8. In a machine for making book matches and in combination, an endless conveyer, means for feeding match book cover blanks thereto, a second endless conveyer parallel to the first endless conveyer for feeding 10 match strips thereto so that a match strip is supplied and placed upon each match book cover blank, devices co-acting with the first aforesaid endless conveyer during the travel thereof for folding both ends of each 15 cover blank over its match strip to position thereon to form a cover therefor, and means for then securing each match strip to its cover.

9. In a machine for making book matches 20 and in combination, an endless conveyer, means for feeding match book cover blanks thereto, a second endless conveyer parallel to the first conveyer for feeding match strips thereto so that a match strip is supplied and 25 placed upon each match book cover blank, devices co-acting with the first aforesaid endless conveyer during the travel thereof for folding both ends of each cover blank over its match strip to position thereon to 30 form a cover therefor, means for pressing each cover to position around its match strip, and means operative when the covers are in this pressing position for securing each match strip to its cover.

- 35 ~10. In a machine for making book matches and in combination, a unitary means for receiving and conveying match book cover blanks and match strips thereon, devices co-acting with the said means while conveying 40 the said match book cover blanks and match strips for folding both ends of each blank to position over its match strip to form a cover therefor, means for securing each match strip within its cover, devices operative after 45 the match strips have been secured in their covers for partially removing the match books from the conveyer, and devices for applying a striking surface to a portion of the exterior of each match book.

- 50 11. In a machine for making book matches and in combination, an endless conveyer, means for feeding thereto match book cover blanks, means for feeding match card strips to the said conveyer so that each match card 55 strip is placed upon a cover blank, means co-operating with the said endless conveyer for folding both ends of each cover blank to position over its match strip while in the conveyer and during the movement thereof, 60 means for securing each match strip within its cover while the parts are still in the conveyer, devices operative after the match strips have been secured in their covers for partially removing the match books from the 65 conveyer, and devices for applying a strik-

ing surface to a portion of the exterior of each match book.

12. In a machine for making book matches and in combination, an endless conveyer, means for feeding match book cover blanks thereto, a second endless conveyer for feeding match strips to the first aforesaid conveyer so that a match strip is supplied and placed upon each match book cover blank, devices co-acting with the first aforesaid 75 endless conveyer during the travel thereof for folding both ends of each cover blank to position over its match strip to form a cover therefor, means for securing each match strip to its cover, devices operative after the match strips have been secured in their covers for partially removing the match books from the conveyer, and devices for applying a striking surface to a portion of the exterior of each match book. 80

13. In a machine for making book matches and in combination, an endless conveyer, blocks secured to one side thereof in spaced positions, providing for intervening pockets, means for feeding match book cover blanks 90 so that they are delivered one at a time to the said pockets in the endless conveyer, means for feeding match strips to the said conveyer so that each match strip enters one of the said pockets in the said conveyer and falls upon its cover blank, and means for folding both ends of each cover blank over its match strip to position thereon to form a cover therefor while the said parts are still within their pocket in said conveyer. 95

14. In a machine for making book matches and in combination, an endless conveyer, blocks secured to one side thereof in spaced positions, providing for intervening pockets, means for feeding match book cover blanks 100 so that they are delivered one at a time to the said pockets in the endless conveyer, means for feeding match strips to the said conveyer so that each match strip enters one of the said pockets in the said conveyer and falls upon its cover blank, means for folding both ends of each cover blank over its match strip to position thereon to form a cover therefor while the said parts are still within their pocket in said conveyer, and means for then securing each match strip to its cover while in their pocket in the conveyer. 110

15. In a machine for making book matches and in combination, an endless conveyer, blocks secured to one side thereof in spaced positions, providing for intervening pockets, means for feeding match book cover blanks 115 so that they are delivered one at a time to the said pockets in the endless conveyer, means for feeding match strips to the said conveyer so that each match strip enters one of the said pockets in the said conveyer and falls upon its cover blank, means for folding both ends of each cover blank over its match 120

- 125
- 130

- strip to position thereon to form a cover therefor while the said parts are still within their pocket in the conveyer, means for pressing each cover to position around its match strip, and means operative while the covers are so pressed in position and while the parts are still in the conveyer for securing each match strip to its cover.

16. In a machine for making book matches and in combination, an endless conveyer, a plurality of blocks secured thereto in equally spaced positions providing for intermediate pockets, means for feeding match book cover blanks so that each one separately is delivered to one of the said pockets in the endless conveyer, a second endless conveyer adapted to feed match strips successively so that each match strip is delivered into one of the pockets on the first aforesaid conveyer in a position superimposed upon its cover blank, and means co-acting with the first aforesaid conveyer during the travel thereof for folding both ends of each cover blank over its match strip to position thereon to form a cover therefor.

17. In a machine for making book matches and in combination, an endless conveyer, a plurality of blocks secured thereto in equally spaced positions providing for intermediate pockets, means for feeding match book cover blanks so that each one separately is delivered to one of the said pockets in the endless conveyer, a second endless conveyer adapted to feed match strips successively so that each match strip is delivered into one of the pockets on the first aforesaid conveyer in a position superimposed upon its cover blank, means co-acting with the first aforesaid conveyer during the travel thereof for folding both ends of each cover blank over its match strip to position thereon to form a cover therefor, and means for securing each match strip to its cover while the same is still in its pocket in the conveyer.

18. In a machine for making book matches and in combination, an endless conveyer, a plurality of blocks secured thereto in equally spaced positions providing for intermediate pockets, means for feeding match book cover blanks so that each one separately is delivered to one of the said pockets in the endless conveyer, a second endless conveyer adapted to feed match strips successively so that each match strip is delivered into one of the pockets on the first aforesaid conveyer in a position superimposed upon its cover blank, means co-acting with the first aforesaid conveyer during the travel thereof for folding both ends of each cover blank over its match strip to position thereon to form a cover therefor, means for pressing each cover to position against its match strip, and means operative while the cover is so pressed in position for securing the match strip to its cover.

19. In a machine for making book matches and in combination, a device for receiving match book cover blanks and match strips thereon, means for imparting an intermittent movement to the said device, and devices co-acting with the aforesaid device during the travel thereof for folding both ends of the cover blanks over the match strips to provide covers therefor.

20. In a machine for making book matches and in combination, devices for receiving match book cover blanks and match strips superimposed thereon, means for imparting an intermittent movement to the said devices, means co-acting with the said devices during the travel thereof for folding both ends of each blank over its match strip to form a cover therefor, and means for securing each match strip within its cover.

21. In a machine for making book matches and in combination, devices for receiving match book cover blanks and match strips superimposed thereon, means for imparting an intermittent movement to the said devices, means co-acting with the said devices during the travel thereof for folding both ends of each blank over its match strip to form a cover therefor, means for pressing each cover to position around its match strip, and means for securing each match strip within its cover.

22. In a machine for making book matches and in combination, an endless conveyer, means for imparting an intermittent movement to the said endless conveyer, means for feeding match book cover blanks to the said conveyer, means for feeding match strips to the said conveyer so that each match strip is placed upon a cover blank, and means for folding both ends of each cover blank over its match strip to position thereon to form a cover therefor.

23. In a machine for making book matches and in combination, an endless conveyer, means for imparting an intermittent movement to the said endless conveyer, means for feeding match book cover blanks to the said conveyer, means for feeding match strips to the said conveyer so that each match strip is placed upon a cover blank, means for folding both ends of each cover blank over its match strip to position thereon to form a cover therefor, and means for securing each match strip within its cover.

24. In a machine for making book matches and in combination, an endless conveyer, means for imparting an intermittent movement to the said endless conveyer, means for feeding match book cover blanks to the said conveyer, means for feeding match strips to the said conveyer so that each match strip is placed upon a cover blank, means co-acting with said endless conveyer during the movement thereof for folding both ends of each cover blank over its match strip to provide covers therefor.

strip to position thereon to form a cover therefor, means for pressing each cover around its match strip, and means operative while the said cover is pressed to position for securing each match strip within its cover.

25. In a machine for making book matches and in combination, an endless conveyer, means for feeding match book cover blanks 10 to the said conveyer, a second endless conveyer adapted to feed match strips to the said first conveyer, a unitary means for imparting an intermittent movement to both the said conveyers, and means co-acting with 15 the first aforesaid conveyer for folding both ends of each cover blank around its match strip to position thereon to form a cover therefor.

26. In a machine for making book matches 20 and in combination, an endless conveyer, means for feeding match book cover blanks to the said conveyer, a second endless conveyer adapted to feed match strips to the said first conveyer, a unitary means for imparting an intermittent movement to both 25 the said conveyers, means co-acting with the first aforesaid conveyer for folding both ends of each cover blank around its match strip to position thereon to form a cover 30 therefor, and means for securing each match strip within its cover.

27. In a machine for making book matches and in combination, an endless conveyer, means for feeding match book cover blanks 35 to said conveyer, a second endless conveyer adapted to feed match strips to the said first conveyer, means for imparting an intermittent movement to both the said conveyers, means for pressing each cover to 40 position around its match strip, means co-acting with the first aforesaid conveyer during the travel thereof for folding both ends of each cover blank to position over its match strip to form a cover therefor, and 45 means operative while the cover is so pressed to position for securing the match strip within the same.

28. In a machine for making book matches and in combination, an endless conveyer, 50 devices for feeding a continuous strip of paper stock, means for cutting the said paper stock to form match book cover blanks, which, as they are cut from the said strip of stock, drop upon the conveyer, means 55 for feeding a match strip to each cover blank upon the conveyer, and means co-acting with the conveyer to fold both ends of each blank over its match strip to position thereon to form a cover therefor.

60 29. In a machine for making book matches and in combination, an endless conveyer, devices for feeding a continuous strip of paper stock, means for cutting the said paper stock to form match book cover blanks,

which, as they are cut from the said strip of stock, drop upon the conveyer, means for feeding a match strip to each cover blank upon the conveyer, means co-acting with the conveyer during the movement thereof to fold both ends of each blank over its match strip to position thereon to form a cover therefor, and means securing each match strip within its cover.

30. In a machine for making book matches and in combination, an endless conveyer, 75 devices for feeding a continuous strip of paper stock, means for cutting the said paper stock to form match book cover blanks, which, as they are cut from the said strip of stock, drop upon the conveyer, means for 80 feeding a match strip to each cover blank upon the conveyer, means co-acting with the conveyer during the movement thereof to fold both ends of each blank over its match strip to position thereon to form a cover therefor, means for pressing each cover to position around its match strip, and means operative when the cover is so 85 pressed to position for securing the match strip therein.

31. In a machine for making book matches and in combination, an endless conveyer, means for imparting a regular intermittent movement to the said conveyer, devices for feeding a continuous strip of paper stock, 95 means for cutting the said paper stock to form a match book cover blank therefrom each time the endless conveyer stops so that the cover blank as cut from the strip falls upon the said conveyer, means for feeding a match strip to each cover blank upon the conveyer, and means co-acting with the said conveyer during the movement thereof to fold both ends of each cover blank over its match strip to form a cover therefor.

32. In a machine for making book matches and in combination, an endless conveyer, means for imparting a regular intermittent movement to the said conveyer, devices for feeding a continuous strip of paper stock, 110 means for cutting the said paper stock to form match book cover blanks therefrom each time the endless conveyer stops so that the cover blank as cut from the strip falls upon the said conveyer, means for feeding a match strip to each cover blank upon the conveyer, means co-acting with the said conveyer during the movement thereof to fold both ends of each cover blank to position over its match strip to form a cover therefor, 115 and means for securing each match strip within its cover.

33. In a machine for making book matches and in combination, an endless conveyer, means for imparting a regular intermittent movement to the said conveyer, devices for feeding a continuous strip of paper stock, 125 means for cutting the said paper stock to

form a match book cover blank therefrom each time the endless conveyer stops so that the cover blank as cut from the strip falls upon the said conveyer, means for feeding 5 a match strip to each cover blank upon the conveyer, means co-acting with the said conveyer during the movement thereof to fold each cover blank to position over its match strip to form a cover therefor, means for 10 pressing each cover to position around its match strip, and means operative while the cover is so held in position for securing the match strip within the same.

34. In a machine for making book 15 matches and in combination, an endless conveyer, devices for feeding a strip of paper stock, means for cutting said paper stock to form match book cover blanks therefrom, which, as they are cut from the said strip, 20 fall upon the said conveyer, a second endless conveyer, means for imparting a regular intermittent movement to both the said endless conveyers, devices for cutting match strips as the same are fed by the said second 25 endless conveyer, permitting the sections of the match strips, as severed, to fall upon the cover blanks on the first aforesaid endless conveyer, and means co-acting with the first aforesaid endless conveyer for folding 30 each cover blank over its section of match strip to form a cover therefor.

35. In a machine for making book matches and in combination, an endless conveyer, devices for feeding a strip of paper stock, 35 means for cutting said paper stock to form match book cover blanks therefrom, which, as they are cut from the said strip, fall upon the said conveyer, a second endless conveyer, means for imparting a regular intermittent movement to both the said endless conveyers, devices for cutting match strips as the same are fed by the said second endless conveyer, permitting the sections of the match strips, as severed, to fall upon the 45 cover blanks on the first aforesaid endless conveyer, means co-acting with the first aforesaid endless conveyer for folding each cover blank over its section of match strip to form a cover therefor, and means for 50 securing each section of match strip within its cover.

36. In a machine for making book matches and in combination, an endless conveyer, devices for feeding a strip of paper stock, 55 means for cutting said paper stock to form match book cover blanks therefrom, which, as they are cut from the said strip, fall upon the said conveyer, a second endless conveyer, means for imparting a regular intermittent movement to both the said 60 endless conveyers, devices for cutting match strips as the same are fed by the second endless conveyer, permitting the sections of the match strips, as severed, to fall upon the 65 cover blanks on the first aforesaid endless

conveyer, means co-acting with the first aforesaid endless conveyer for folding each cover blank over its section of match strip to form a cover therefor, means for pressing each match book cover to position around its section of a match strip, and means operative while the cover is so pressed to position for securing the section of match strip therein. 70

37. In a machine for making book 75 matches and in combination, an endless conveyer, devices for feeding a strip of paper stock, means for cutting the said paper stock to form match book cover blanks therefrom, which, as they are cut from the said strip, drop upon the said conveyer, a second endless conveyer adapted to feed match strips, devices for cutting the said match strips into sections of predetermined length and permitting the same, as cut, to drop upon the cover blanks on the first aforesaid conveyer, means co-acting with the first aforesaid conveyer during the travel thereof for folding each cover blank over its section of the match strip to form a cover therefor. 80 85 90

38. In a machine for making book matches and in combination, an endless conveyer, devices for feeding a strip of paper stock, means for cutting the said paper stock to form match book cover blanks therefrom, 95 which, as they are cut from the said strip, drop upon the said conveyer, a second endless conveyer adapted to feed match strips, devices for cutting the said match strips into sections of predetermined length and permitting the same, as cut, to drop upon the cover blanks on the first aforesaid conveyer, means co-acting with the first aforesaid conveyer during the travel thereof for folding each cover blank over its section of the match strip to form a cover therefor, and means for securing each section of match strip within its cover. 100 105

39. In a machine for making book matches and in combination, an endless conveyer, devices for feeding a strip of paper stock, means for cutting the said paper stock to form match book cover blanks therefrom, which, as they are cut from the said strip, drop upon the said conveyer, a second endless conveyer adapted to feed match strips, devices for cutting the said match strips into sections of predetermined length and permitting the same, as cut, to drop upon the cover blanks on the first aforesaid conveyer, means for pressing each cover to position around its section of the match strip, and means operative when the cover is so pressed to position for securing the section of match strip therein. 110 115 120

40. In a machine for making book matches and in combination, an endless conveyer, a plurality of blocks secured to one surface thereof in spaced positions providing for intervening pockets, rolls for feeding a strip 125 130

- of paper stock, means for cutting the said paper stock to form match book cover blanks therefrom, the said match book cover blanks as cut from the paper stock falling successively into the said pockets between the blocks on the endless conveyer, a second endless conveyer, projections carried thereby adapted to engage slots in the edge of a match strip in order to feed the same, means for imparting a regular intermittent movement to both the said conveyers and the said feed rolls, devices for cutting the said match strip into predetermined lengths and permitting each section as cut from the match strip to fall upon a cover blank within a pocket on the first aforesaid conveyer, and means co-acting with the first aforesaid conveyer for folding each cover blank over its section of match strip to form a cover therefor.
41. In a machine for making book matches and in combination, an endless conveyer, a plurality of blocks secured to one surface thereof in spaced positions providing for intervening pockets, rolls for feeding a strip of paper stock, means for cutting the said paper stock to form match book cover blanks therefrom, the said match book cover blanks as cut from the paper stock falling successively into the said pockets between the blocks on the endless conveyer, a second endless conveyer, projections carried thereby adapted to engage slots in the edge of a match strip in order to feed the same, means for imparting a regular intermittent movement to both the said conveyers and the said feed rolls, devices for cutting the said match strip into predetermined lengths and permitting each section as cut from the match strip to fall upon a cover blank within a pocket on the first aforesaid conveyer, means co-acting with the first aforesaid conveyer for folding each cover blank over its section of match strip to form a cover therefor, and means for securing each section of match strip within its cover.
42. In a machine for making book matches and in combination, an endless conveyer, a plurality of blocks secured to one surface thereof in spaced positions providing for intervening pockets, rolls for feeding a strip of paper stock, means for cutting the said paper stock to form match book cover blanks therefrom, the said match book cover blanks as cut from the paper stock falling successively into the said pockets between the blocks on the endless conveyer, a second endless conveyer, projections carried thereby adapted to engage slots in the edge of a match strip in order to feed the same, means for imparting a regular intermittent movement to both the said conveyers and the said feed rolls, devices for cutting the said match strip into predetermined lengths and permitting each section as cut from the match strip to fall upon a cover blank within a pocket on the first aforesaid conveyer, means co-acting with the first aforesaid conveyer for folding each cover blank over its section of match strip to form a cover therefor, and means for securing each section of match strip within its cover.
43. In a machine for making book matches and in combination, an intermittently moving device adapted to receive match book cover blanks and superimposed match strips, and a series of folders co-acting with said device during the movement thereof for turning both of the ends of each match book cover blank to position over its match strip to form a cover therefor.
44. In a machine for making book matches and in combination, an intermittently moving device adapted to receive match book cover blanks and superimposed match strips, a series of folders co-acting with said device during the movement thereof for turning both of the ends of each match book cover blank over its match strip to form a cover therefor, and means for then securing each match strip within its cover.
45. In a machine for making book matches and in combination, an intermittently moving device, means associated therewith and adapted to form spaced pockets in which are received match book cover blanks and superimposed match strips in such positions that the ends of the cover blanks extend unequal distances beyond the ends of the match strips, forming a long and a short end to each match card cover blank, a folder for turning up the long end of each cover blank, a folder for turning down the long end of each cover blank over its match strip, and a folder for turning down the short end of each cover blank over the adjacent outer surface of the long end of the cover blank.
46. In a machine for making book matches and in combination, an intermittently moving device, means associated therewith and adapted to form spaced pockets in which are received match book cover blanks and superimposed match strips in such positions that the ends of the cover blanks extend unequal distances beyond the ends of the match strips, forming a long and a short end to each match card cover blank, a folder for turning up the long end of each cover blank, a folder for turning up the short end of each cover blank, a folder for turning down the long end of each cover blank over its match strip, a folder for turning down the short end of each cover blank over the adjacent outer surface of the long end of the cover blank, and means for securing each match strip in its cover.
47. In a machine for making book matches and in combination, a main shaft,

- an auxiliary shaft, means for imparting a regular intermittent rotary motion to the said auxiliary shaft from the main shaft, an endless conveyer actuated by the said auxiliary shaft, the said endless conveyer being adapted to receive match book cover blanks and superimposed match strips, and means coacting with the said endless conveyer during the movement thereof for folding both ends of each cover blank over its match strip to form a cover therefor. 5
48. In a machine for making book matches and in combination, a main shaft, an auxiliary shaft, means for imparting a regular intermittent rotary motion to the said auxiliary shaft from the main shaft, an endless conveyer actuated by the said auxiliary shaft, the said endless conveyer being adapted to receive match book cover blanks and superimposed match strips, means coacting with the said endless conveyer during the movement thereof for folding both ends of each cover blank over its match strip to form a cover therefor, and means for securing each match strip within its cover. 10
49. In a machine for making book matches and in combination, a main shaft, an auxiliary shaft, devices for transforming a continuous rotary motion of the said main shaft into a regular intermittent rotary motion in the auxiliary shaft, an endless conveyer actuated by the said auxiliary shaft, means for feeding match book cover blanks to the said endless conveyer, means for feeding match strips and depositing the same upon the cover blanks on the endless conveyer, and means coacting with the conveyer for folding both ends of each cover blank over its match strip to form a cover therefor. 15
50. In a machine for making book matches and in combination, a main shaft, an auxiliary shaft, devices for transforming a constant rotary motion of the main shaft into an intermittent rotary motion in the auxiliary shaft, an endless conveyer actuated by the auxiliary shaft, means for feeding a strip of paper stock and for severing the same to make match book cover blanks which are deposited one at a time upon the said endless conveyer, devices for supplying a match strip in a superimposed position upon each cover blank, means coacting with the conveyer for feeding both ends of each cover blank over its match strip, and means for securing each match strip within its cover. 20
51. In a machine for making book matches and in combination, a main shaft, an auxiliary shaft, devices for transforming a constant rotary motion of the main shaft into an intermittent rotary motion in the auxiliary shaft, an endless conveyer actuated by the auxiliary shaft, rolls also actuated by the auxiliary shaft and adapted to intermittently feed a strip of paper stock, devices for cutting a match book cover blank from said strip of paper stock each time the said rolls and endless conveyer are stopped and permitting that portion of the paper strip, cut as aforesaid, to drop upon the endless conveyer, means for feeding a match strip to a superimposed position upon each cover blank on the conveyer, means for folding each cover blank over its match strip to provide a cover therefor, and means for securing each match strip within its cover. 25
52. In a machine for making book matches and in combination, a main shaft, an auxiliary shaft, devices for transforming a constant rotary motion of the main shaft into an intermittent rotary motion in the auxiliary shaft, an endless conveyer actuated by the auxiliary shaft, rolls also actuated by the auxiliary shaft and adapted to intermittently feed a strip of paper stock, devices for cutting a match book cover blank from said strip of paper stock each time the said rolls and endless conveyer are stopped and permitting that portion of the paper strip, cut as aforesaid, to drop upon the endless conveyer, a second endless conveyer adapted to engage and feed strips of matches, a cutter device adapted to sever the strip of matches into sections in predetermined lengths, one section being cut therefrom each time the feed rolls and endless conveyers are stopped, and each section, as cut from its match strip, is permitted to fall upon one of the cover blanks on the first aforesaid endless conveyer, means for folding each cover blank over its section of match strip, and means for securing each match strip within its cover. 30
53. In a machine for making book matches and in combination, a main shaft, an auxiliary shaft, devices for transforming a constant rotary motion of the main shaft into an intermittent rotary motion in the auxiliary shaft, an endless conveyer actuated by the auxiliary shaft, rolls also actuated by the auxiliary shaft and adapted to intermittently feed a strip of paper stock, devices for cutting a match book cover blank from said strip of paper stock each time the said rolls and endless conveyer are stopped and permitting that portion of the paper strip, cut as aforesaid, to drop upon the endless conveyer, a second endless conveyer adapted to engage and feed strips of matches, a cutter device adapted to sever the strip of matches into sections of predetermined lengths, one section being cut therefrom each time the feed rolls and endless conveyers are stopped, and each section, as cut from its match strip, is permitted to fall upon one of the cover blanks on the first aforesaid endless conveyer, means for folding each cover blank over its section of match strip, means

for securing each match strip within its cover, a pusher device adapted to partially remove each match book on the endless conveyer, and devices for applying a striking surface to a portion of the cover of each match book.

54. In a machine for making book matches and in combination, a main shaft, an auxiliary shaft, devices for transforming a constant rotary motion of the main shaft into an intermittent rotary motion in the auxiliary shaft, an endless conveyer, actuated by the said auxiliary shaft, a series of spaced blocks secured to the said endless conveyer providing intervening pockets, rolls, means for actuating the said rolls from the said auxiliary shaft to feed a strip of paper stock predetermined distances at a time, devices actuated from the main shaft for severing cover blanks from the said strip of material and permitting the same to drop, as severed, into the pockets in the said endless conveyer, a second endless conveyer, means for actuating the same from the said auxiliary shaft, fingers carried by the said second endless conveyer adapted to engage notches in one edge of the match strips in order to intermittently feed the same, devices actuated from the main shaft for cutting each match strip into sections of predetermined lengths and permitting each section as severed from its match strip to fall upon a cover blank within one of the pockets on the first aforesaid endless conveyer, means for folding each cover blank over its section of match strip, and means for securing each section of match strip within its cover.

55. In a machine for making book matches and in combination, a main shaft, an auxiliary shaft, devices for transforming a constant rotary motion of the main shaft into an intermittent rotary motion in the auxiliary shaft, a series of spaced blocks secured to the said endless conveyer providing intervening pockets, rolls, means for actuating the said rolls from the said auxiliary shaft to feed a strip of paper stock predetermined distances at a time, devices actuated from the main shaft for severing cover blanks from the said strip of material and permitting the same to drop, as severed, into the pockets in the said endless conveyer, a second endless conveyer, means for actuating the same from the said auxiliary shaft, fingers carried by the said second endless conveyer adapted to engage notches in one edge of the match strips in order to intermittently feed the same, devices actuated from the main shaft for cutting each match strip into sections of predetermined lengths and permitting each section as severed from its match strip to fall upon a cover blank within one of the pockets on the first aforesaid endless conveyer, a series of folders

adapted to turn the ends of each cover blank over its match strip, and a stapling mechanism driven from the main shaft for securing each section of match strip within its cover.

56. In a machine for making book matches and in combination, a main shaft, an auxiliary shaft, devices for transforming a constant rotary motion of the main shaft into an intermittent rotary motion in the auxiliary shaft, a series of spaced blocks secured to the said endless conveyer providing intervening pockets, rolls, means for actuating the said rolls from the said auxiliary shaft to feed a strip of paper stock predetermined distances at a time, devices actuated from the main shaft for severing cover blanks from the said strip of material and permitting the same to drop, as severed, into the pockets in the said endless conveyer, a second endless conveyer, means for actuating the same from the said auxiliary shaft, fingers carried by the said second endless conveyer adapted to engage notches in one edge of the match strips in order to intermittently feed the same, devices actuated from the main shaft for cutting each match strip into sections of predetermined lengths and permitting each section as severed from its match strip to fall upon a cover blank within one of the pockets on the first aforesaid endless conveyer, a series of folders adapted to turn the ends of each cover blank over its match strip, a stapling mechanism driven from the main shaft for securing each section of match strip within its cover, and means for applying a strip of friction paint to a portion of each cover blank.

57. A machine for making book matches comprising means for feeding a strip of paper stock a predetermined distance at spaced intervals, means for cutting the strip of paper stock into cover blanks, means for receiving each cover blank as cut from the strip of paper stock, means for placing a section of match card upon each cover blank, and means coacting with the said means for receiving the cover blanks for folding both ends of each cover blank over its match strip to form a cover therefor.

58. A machine for making book matches comprising means for feeding a strip of paper stock a predetermined distance at spaced intervals, means for cutting the strip of paper stock into cover blanks, means for receiving each cover blank as cut from the strip of paper stock, means for placing a section of match card upon each cover blank, means coacting with the said means for receiving the cover blanks for folding both ends of each cover blank over its match strip to form a cover therefor, and means for securing each match strip within its cover blank.

59. A machine for making book matches comprising means for feeding a strip of paper stock a predetermined distance at spaced intervals, devices for embossing the paper stock each time the feed movement thereof ceases, means for cutting the strip of paper stock into cover blanks, means for receiving each cover blank as cut from the strip of paper stock, means for placing a section of match card upon each cover blank, means co-acting with the said means for receiving the cover blanks for folding both ends of each cover blank over its match strip to form a cover therefor, and means for securing each match strip within its cover blank. 65
60. A machine for making book matches comprising means for feeding a strip of paper stock a predetermined distance at regular stated intervals, means for cutting the strip of paper stock into cover blanks, means for receiving each cover blank as cut from the strip of paper stock and continuing the movement thereof in the machine, means for engaging, feeding and cutting match strips so that each section cut therefrom is permitted to fall upon a cover blank, and means for folding each cover blank over its match strip to form a cover therefor. 70
61. A machine for making book matches comprising means for feeding a strip of paper stock a predetermined distance at regular stated intervals, means for cutting the strip of paper stock into cover blanks, means for receiving each cover blank as cut from the strip of paper stock and continuing the movement thereof in the machine, means for engaging, feeding and cutting match strips so that each section cut therefrom is permitted to fall upon a cover blank, and means for folding each cover blank over its match strip to form a cover therefor. 75
62. A machine for making book matches comprising means for feeding a strip of paper stock a predetermined distance at regular stated intervals, devices for embossing the strip of paper stock each time the feed thereof is stopped, means for cutting the strip of paper stock into cover blanks, means for receiving each cover blank as cut from the strip of paper stock and continuing the movement thereof in the machine, means for engaging, feeding and cutting match strips so that each section cut therefrom is permitted to fall upon a cover blank, means for folding each cover blank over its match strip to form a cover therefor, and means for securing each section of match strip within its cover. 80
63. A machine for making book matches comprising means for feeding a strip of paper stock a predetermined distance at regular stated intervals, devices for embossing the strip of paper stock each time the feed thereof is stopped, means for cutting the strip of paper stock into cover blanks, means for receiving each cover blank as cut from the strip of paper stock and continuing the movement thereof in the machine, means for engaging, feeding and cutting match strips so that each section cut therefrom is permitted to fall upon a cover blank, means for folding each cover blank over its match strip to form a cover therefor, and means for securing each section of match strip within its cover. 85
64. In a machine for making book matches and in combination, an endless conveyer, devices for feeding a strip of paper stock and cutting the same into predetermined lengths, forming match book cover blanks, and delivering each blank, when formed, upon the endless conveyer, devices for feeding and cutting match strips into sections of predetermined lengths and delivering each section of match strip upon one of the cover blanks in the conveyers, devices associated with the aforesaid means for clamping the match strips in position while the same is being cut, and devices co-acting with the said conveyer during the movement thereof for folding both ends of each cover blank to position over its section of match strip to form a cover therefor. 90
65. In a machine for making book matches and in combination, an intermittently moving endless conveyer, devices for feeding a strip of material, cutting match book cover blanks predetermined lengths therefrom, and delivering each cover blank as severed from said strip to the said endless conveyer, a second intermittently moving endless conveyer for feeding match strips, devices for cutting the said match strips into sections of predetermined lengths, permitting each section of the match strip to fall on a cover blank in the first aforesaid conveyer, devices associated with the last aforesaid conveyer for clamping the match strips in position while the same are cut into sections, means co-acting with the first aforesaid conveyer for folding the cover blanks over the match strips to provide covers therefor, and means for securing each match strip within its cover. 95
